UNITED STATES PATENT OFFICE.

THOMAS GORDON, OF PHILADELPHIA, PENNSYLVANIA, ASSIGNOR OF ONE-HALF TO EMANUEL STEIN, OF SAME PLACE.

GAS-COCK.

SPECIFICATION forming part of Letters Patent No. 318,978, dated June 2, 1885.

Application filed April 28, 1884. (No model.)

To all whom it may concern:

Be it known that I, THOMAS GORDON, of the city of Philadelphia, in the State of Pennsylvania, have invented a certain new and useful Improvement in Gas-Cocks, of which the following is a specification.

My invention relates to devices for regulating the flow of gas through a pipe; and it consists in substituting a solid plug recessed on its external surface and bored out in the direction of its length to the depth of such recess to admit of the insertion of a central core instead of a hollow plug, and of combining therewith a central core moving longitudinally by screw-thread, or otherwise covering or uncovering, as desired, a gas port or passage drilled through the cock-plug in the center of its recessed surface, as hereinafter more fully described.

In the accompanying drawings, Figure I is a front elevation of my improved device; Fig. II, a vertical section thereof through the center; and Fig. III, a view of the solid plug, showing one side recessed or drilled out, and showing also the upper end of the central core.

It has heretofore been the practice to make the plug hollow, with portions of the surface cut away, so that when turned by the handle the gas could pass, by means of the cut-out portions, through such hollow plug from one side of the pipe to the other. Instead of so doing, I make the plug solid, and drill out a semi-spherical recess, A, on the external surface of the plug, to form a gas port or passage, or two semi-spherical recesses, A A, on opposite sides, so that when the plug is turned in the pipe B the gas may flow through the space thus drilled out from one side of the pipe to the other; and in order to regulate with a greater nicety and accuracy the flow of gas, I drill out the plug in the direction of its length to the center of the external recess or gas-passage, A, at which point I make a cross-drill, C, through the plug to form a second gas-passage through the plug when it is so turned in the pipe as to close the gas-port A. In the longitudinal recess D in the plug is inserted a central metal core, E, which may be screw-threaded at its upper end, to be moved by hand or otherwise, and the point thereof

is made conical to fit more accurately the corresponding-shaped base of the recess, so that in practice when the plug would, by being turned, otherwise shut off the flow of gas, the central core may be moved backward or forward to admit a more or less greater flow of gas through the cross-drilled recess in the plug, and thus regulate the same to a nicety.

I am aware that it is not new to construct a gas-cock with a hollow plug grooved circumferentially and a central screw working in the hollowed-out portion of the cock, so as to serve as a double gas-valve to divide the supply and lead it to two jets or tubes simultaneously, this having been patented to F. D. Bliss, April 24, 1877, by Letters Patent No. 189,916, and I do not claim the invention therein described, my improvements relating solely to a by-pass cock, in which the plug is solid and has gas-passages in the form of longitudinal grooves on its surface, and having a central core, whereby two gas-passages are formed on opposite sides of the cock, one open while the other is closed, in order to more accurately regulate the supply of gas passing through the same.

Having thus described my invention, what I claim as new, and desire to secure by Letters Patent, is—

A gas cock or valve adapted to fit a gas-pipe and regulate the flow of gas therein, consisting of a plug recessed on its periphery to form a gas port or passage, A, and cross-drilled through such recess to form a second gas port or passage, C, open when the first is closed, and provided also with a central longitudinal opening, D, in combination with a central core, E, fitting in said opening D, and capable of being moved therein to cover and uncover at pleasure said gas-port C wholly or partially, as may be desired, said device being constructed and operating substantially as and for the purpose set forth.

In witness whereof I have signed my name to this specification in the presence of witnesses.

THOMAS GORDON.
